Specification of Letters Patent.

Patented Oct. 20, 1914.

Application filed August 18, 1909. Serial No. 513,637.

To all whom it may concern:

Be it known that I, EDMUND B. WEDMORE, a subject of the King of Great Britain, residing at Rugby, England, have invented 5 certain new and useful Improvements in Protective Devices, of which the following is a specification.

My invention relates to protective devices for electrical apparatus and more particularly to protective devices for relays of the time limit type, and the object of my invention is to produce a time limit device which is simple and reliable, which has a wide range of adjustment, and which will act 15 instantaneously in case the abnormal conditions on the circuit to be protected exceed predetermined limits.

In carrying out my invention, the mechanism is so constructed that two coöperating 20 members, such as the contacts of a relay, are brought into definite relation to each other to open the circuit to be protected. The mechanism is so arranged that the coöperating members or contacts approach each 25 other as soon as the abnormal conditions appear upon the circuit to be protected, the movement of one of the contacts being at a definite and predetermined rate, while the movement of the other contact and the position 30 assumed by it is dependent upon the conditions in the circuit to be protected. The coöperating member or contact which moves at a predetermined rate may be driven by clock work or any suitable mechanism which will give it a definite rate of 35 movement unaffected by the current in the circuit to be protected, while the other member or contact is actuated by any suitable electro-responsive device, such as a solenoid, 40 the movement of the second member being controlled by some suitable controlling or damping device such as a dash pot.

My invention may best be understood in connection with the accompanying drawings, which show one of the various forms in 45 which it may be embodied and in which—

Figure 1 is a fragmentary elevation, partly in section, of one embodiment of my invention in the form of a three phase relay; Fig. 2 an end view of the relay shown in Fig. 1; Fig. 3 a modified form of relay which is self-restoring; Fig. 4 is a diagrammatic illustration of a relay having a thermostatic element; and Fig. 5 is a diagram-

matic illustration of a relay having as one 55 element an ammeter movement.

In the embodiment of the invention shown in Figs. 1 and 2, a base or panel 1 is provided with a support 2 and brackets 3 for holding relay coils 4, 5 and 6, each of which 60 is connected to one phase of a three phase system. Each coil is provided with an armature or movable plunger 7 which takes up a position in the coil corresponding to the value of the current flowing through the coil 65 and hence the movement and position of the plunger 7 of each coil is dependent upon the conditions in the circuit to which the coils are connected. The movement of each plunger may be controlled in any suitable manner, and in the specific embodiment shown in 70 the drawings each plunger is controlled by means of a piston 8 carried on a rod 9 and sliding in a tube 10. Above the plungers 7, a tripping bar 11 is pivoted at 12 to brackets 75 13 mounted on the base 1, and when any or all of the plungers rise, their extremities 14 will engage with and lift the bar 11. Mounted on, but insulated from the bar 11 is a projecting member or contact 15 connected 80 with the tripping circuit of the oil switch or other circuit breaking device which controls the three phase system to which the relay coils 4, 5 and 6 are connected. Directly above the member or contact 15 is mounted 85 a coöperating member or contact which is moved toward the contact 15 at a definite and uniform rate and which engages the contact 15 to close the tripping circuit and thereby cause the circuit breaking device to 90 be operated. In the specific embodiment shown in the drawings, the contact or member which coöperates with the contact 15 is made in the form of a snail wheel 16 mounted 95 upon a shaft 17 and insulated from the shaft by an insulated collar 18, said wheel 16 being connected with the tripping circuit and coöperating with the contact 15. The shaft 17 carrying the contact or snail wheel 16 is rotated at a definite and uniform rate 100 by any suitable driving mechanism, such as a clock with an escapement, a fan, or similar device, the driving mechanism being normally restrained by a lug 17^a mounted on the shaft 17 to engage a stop 11^a on the tripping bar 11. The lug 17^a is released and the driving mechanism is set in action by the 105 same conditions which raise any of the plun-

gers 7. Where desired, a cover 19 may be placed over the operating parts of the relay to protect them, and adjustable weights 20 may be secured by set screws 21 to the 5 plungers 7 whereby each plunger may be set to begin its upward movement at any predetermined current value.

The operation of the protective device or relay shown in Figs. 1 and 2 is as follows: 10 If it be assumed that the parts are adjusted so that the plungers begin to rise at 50% overload and the snail wheel contact 16 is in the position shown in Fig. 2, then when any one of the plungers rises, its extremity 14 15 engages the tripping bar 11 and lifts both the bar and the contact 15 upwardly into a position corresponding to the current value, while at the same time the stop 11^a releases the lug 17^a and leaves the shaft free to rotate. 20 As soon as any plunger commences its upward movement, the driving mechanism begins to rotate the shaft 17 and snail wheel or contact 16 and as soon as the latter engages with the contact 15, the tripping circuit 25 is closed and the main switch or circuit breaker automatically opened. At 50% overload, the plungers will rise only a little and the snail wheel would take a predetermined time, say five minutes, to come into 30 engagement with the contact 15 and close the tripping circuit, but if the overload amounts to 100% the tripping bar is lifted higher and the time required for the snail wheel 16 to engage the contact 15 would be 35 reduced to about two minutes, while if the overload reaches 300% the pull on the plunger 7 is so great that the dashpot has but little retarding effect, and contact 15 will be lifted very quickly into engagement with 40 the snail wheel 16.

In order to avoid the necessity of rewinding a clock mechanism for driving the snail wheel 16 a meter movement may be employed to drive the shaft 17 and may be 45 operated from the bus bars. One form in which this modification may be embodied is shown in Fig. 3, in which the relay mechanism is substantially the same as shown in Figs. 1 and 2 and like parts are designated 50 by like reference numerals. The rotating mechanism comprises a meter movement 22 which always runs at substantially the same uniform speed and is automatically set into operation upon the appearance of overload. 55 Any overload which moves the tripping bar 11 closes the circuit through the meter movement by means of a spring contact 22^a which engages a co-operating contact as long as the tripping bar 11 is lifted out of normal position. 60 A meter movement drives the contact or snail wheel 16 through a clutch, one member 23 of which is driven by the motor mechanism and engages with the other member 24 when the latter is thrown into mesh 65 with the first member by means of a sole-

noid 25 provided with a movable core or plunger 26 which is rotatably and slidably mounted in holes in the projecting plates 27 and 28, the latter of which also supports the solenoid 25. One end of the plunger 26 carries the clutch member 24 and snail wheel 16, while the other end carries a grooved wheel 29 between which and the bearing 27 a spring 30 is arranged to normally hold the clutch members apart. A cord 31 fixed to the wheel 29 is attached to a weight 32 for rotating the plunger 26.

The operation is as follows: As soon as one of the plungers 7 rises the tripping bar 11 is likewise raised. Upon its initial movement this tripping bar closes the circuit through the meter movement 22 by means of the spring contact 22^a. When the circuit has been so closed, the meter movement 22 begins to rotate and the solenoid 25, being in series with the meter movement, throws the clutch members into engagement, whereupon the snail wheel or contact 16 is rotated and lifts the weight 32. Should the overload cease before the tripping circuit is closed, the solenoid 25 is de-energized, the spring 30 disengages the clutch members and the weight 32 returns the snail wheel or contact 16 to its original position.

Although the invention is shown embodied in the form of a three phase relay, it may equally well be employed on a single phase or polyphase system, and instead of the solenoid and plunger located in each phase of the circuit to be protected, I may use any suitable electro-responsive device, such as an ordinary ammeter movement or a thermostat, as long as the electro-responsive device has a moving part which assumes different positions in response to different current, potential, or other electrical condition on the circuit to be protected. In order to illustrate one of the many ways in which the device may be constructed to embody a thermostatic device, I have shown 100 diagrammatically in Fig. 4 a local circuit containing a battery 33 or some other suitable source of current which is to be closed in accordance with the conditions on the main circuit 34. The circuit closing relay 105 comprises the same driving mechanism as that shown in Figs. 1 and 2 and so connected that the local circuit is closed when the contact 15 engages the snail wheel 16. The 110 position of the contact 15 with relation to the snail wheel 16 is controlled by the thermostatic strip 35 connected in series with the main circuit 34 and proportioned to bend upward as it is heated. A very slight upward movement of the thermostat 35 will 115 move the stop 11^a a sufficient distance to release the driving mechanism and start the snail wheel 16. The extent to which the snail wheel is turned before the local circuit is 120 closed is determined by the position of the 125 130

stop 15, which in turn is dependent upon the extent to which the thermostat 35 is bowed upward.

The invention may also be embodied in the form of relay illustrated diagrammatically in Fig. 5, in which the main circuit 34 is connected to an ammeter 36 provided with some sort of control spring such as a spiral spring 37 preferably so proportioned that the ammeter has a suppressed zero and the moving element will not turn against the control spring until the current reaches a predetermined limit. The moving element of the ammeter carries an arm 38 and when the current of the main circuit exceeds the predetermined limit at which the moving element of the ammeter begins to turn, the position of the arm is determined by the amount which the current in the main circuit exceeds the predetermined limit at which the movement began. The end of the arm 38 controls the stop 11^a of the driving mechanism for the snail wheel 16 and the contact 15 is also carried upon the arm 38 so that the relation of the contact 15 to the snail wheel 16 is determined by and is dependent on the amount of current flowing in the main circuit. As soon as the arm 38 of the ammeter is moved by the excess current the driving mechanism is released, the snail wheel 16 begins to rotate, and after a period of time determined by the position of the arm 38 and the contact 15 the local circuit, including the battery 33, is closed.

While I have described one specific form of carrying out my invention, it will be understood that many modifications may be made without departing from the spirit of my invention, and I therefore do not wish to be restricted to the precise arrangement shown and described, but intend to cover by the appended claims all changes within the spirit and scope of my invention.

What I claim as new and desire to secure by Letters Patent of the United States, is,—

1. An inverse time limit overload relay comprising normally separated coöperating contacts movable into engagement to close the tripping circuit, time actuated mechanism for moving said contacts toward each other at a definite and uniform rate when set in operation and means responsive to overload for instantaneously moving said contacts toward each other a distance dependent upon the extent of overload and for simultaneously rendering said time actuated mechanism operative to move said contacts with a time lag over the remainder of the distance and thereby bring them into engagement.

2. An inverse time limit overload relay for controlling a tripping circuit comprising coöperating contacts normally out of tripping relation, normally inoperative time actuated

mechanism for moving said contacts from any position into tripping relation and means responsive to current in the circuit to be protected for instantaneously setting said contacts in such position that the extent to which they are out of circuit closing relation is dependent upon the amount of current and simultaneously rendering said time actuated mechanism operative to move said contacts from said position into tripping relation.

3. An inverse time limit overload relay comprising contacts normally separated to leave a gap in the tripping circuit, a time limit actuating mechanism for closing the gap between said contacts at a substantially constant rate, and means responsive to overload for instantly rendering the gap between said contacts inversely proportional to the amount of overload and simultaneously starting said time limit mechanism to close said gap at a predetermined rate which is independent of the amount of overload.

4. A time limit circuit controller comprising two relatively movable coöperating contact members normally out of tripping relation, a current responsive device operatively related to one of said movable contact members for instantly moving it to render the extent to which said contact members are out of tripping relation inversely proportional to the extent to which the current in said device exceeds a predetermined amount, time limit actuating means for slowly moving said second contact member at a definite rate to bring said contact members into tripping relation, and means whereby said current responsive device in moving said first contact member simultaneously renders said actuating means operative to move said second contact member toward the first mentioned contact member.

5. An inverse time limit relay comprising relatively movable coöperating contacts, means for yieldingly holding said contacts separated, time limit actuating mechanism for bringing said contacts into engagement at a definite and uniform rate, and means responsive to overload for instantly moving said contacts toward each other to an extent dependent upon the amount of overload and simultaneously rendering said time limit actuating mechanism operative to complete the closing movement of said contacts.

6. An inverse time limit overload relay comprising two relatively movable coöperating contact members, a current responsive device for moving one of said contact members a distance proportional to the amount of overload, a normally inoperative driving mechanism for moving said other contact member from an initial position toward the first contact member at a predetermined rate, means actuated by said current responsive

- device for setting said driving mechanism into operation on appearance of an overload, and means whereby said other contact member is returned to its initial position when the overload disappears.
- 5 7. An inverse time limit current responsive relay comprising a current responsive device, a contact member arranged to be actuated by said device when the current in said device exceeds a predetermined amount, a rotatable contact member mounted to move into engagement with said first mentioned contact member, means controlled by said current responsive device for rotating said 10 rotatable contact member at a predetermined uniform rate when the current in said device exceeds said predetermined amount, and means tending to maintain said rotatable contact member in its initial position 15 when the current in said current responsive device is less than said predetermined amount.
8. A time limit relay comprising a movably mounted contact for a tripping circuit, 20 a time limit actuating mechanism comprising a movable cam shaped member and means for moving said member at a definite rate to complete the tripping circuit through said contact, and means responsive to an abnormal condition on the circuit to be protected for moving said contact in a direction to close the tripping circuit and to an extent dependent upon the extent of the abnormal condition, and simultaneously setting said 25 time limit actuating mechanism into operation to move said cam shaped member to close the tripping circuit.
9. A time limit relay comprising relatively movable coöperating contacts, one of 30 which is provided with a cam surface and the other movably mounted to move from normal position toward said cam surface, time limit actuating mechanism for moving said first mentioned contact at a definite rate 35 to bring said cam surface and said other contact into engagement, and means responsive to an abnormal condition on the circuit to be protected for instantly moving said second contact toward the first a distance dependent upon the extent of said abnormal 40 conditions and simultaneously setting said time limit mechanism into operation.
10. A time limit overload relay for an electric circuit comprising an electromagnet 45 having a movable armature and responsive to current in said circuit, a movable contact member operatively related to said armature and adapted to assume a position proportional to the current in said circuit when 50 said current exceeds a predetermined amount, a rotatable contact member in the form of a snail wheel, actuating means for rotating said rotatable contact member at a predetermined rate, means for setting said 55 actuating means in operation when the cur-

rent in said circuit exceeds a predetermined amount and means for maintaining said rotatable contact member in an initial position when the current in said circuit is less than said predetermined amount.

11. A time limit overload relay comprising two coöperating relatively movable contact members, one of said members having a cam surface, the other of said members being mounted to move into engagement with said cam surface, a time limit actuating mechanism for slowly moving said members relatively to each other to cause the high part of said cam surface and said coöperating contact member to approach each other at a predetermined rate, an electromagnet having a movable armature and responsive to current in the circuit to be protected, said armature being mounted to assume a position dependent upon the amount of overload and operatively related to one of said contact members to carry it toward said other contact member as said armature is moved by said electromagnet.

12. A time limit overload relay comprising a rotatable contact member having a cam surface, an electromagnet having a movable armature and responsive to current in said circuit, a movable contact member operatively related to said armature and adapted to move toward said rotatable contact member and in the plane of said cam surface a distance proportional to the overload in said circuit, a time limit actuating mechanism for slowly rotating said rotatable contact member at a predetermined rate, and means for setting said actuating mechanism in operation when an overload occurs.

13. A time limit overload relay for an electric circuit comprising, a rotatable contact member in the form of a cam, an electromagnet having a movable armature and responsive to current in said circuit, a movable contact member operatively related to said armature and adapted to move toward the edge of said cam a distance inversely proportional to the amount of overload in said circuit and into engagement with said cam upon excessive overload, a time limit actuating mechanism for slowly rotating said cam at a predetermined rate toward engagement with said movable contact, and means for setting said time limit actuating mechanism in operation when said overload occurs.

14. A time limit relay for electric circuits comprising an electromagnet having an armature, a movable contact member operatively related to said armature, said movable contact member being arranged to move a distance proportional to the current in said electromagnet when the current exceeds a predetermined amount, a rotating mechanism adapted to revolve at a predetermined rate, said mechanism being brought into op- 125

eration by any current capable of moving the armature of said electromagnet, a snail wheel contact member adapted to be driven by said rotating mechanism and normally held in inoperative relation to said mechanism, means actuated by said electromagnet for placing said snail wheel contact member in operative relation with said rotating mechanism whereby said snail wheel contact member is rotated at a predetermined rate and comes into engagement with said mov-

able contact member, and means whereby said snail wheel contact member is returned to an initial position when the current through said rotating mechanism is less than 15 a predetermined amount.

In witness whereof, I have hereunto set my hand this tenth day of August, 1909.

E. B. WEDMORE.
